UNITED STATES PATENT OFFICE.

WILLIAM REIFFERSCHEID, OF CHICAGO, ILLINOIS.

ZIGZAG RADIATOR.

1,236,192.

Specification of Letters Patent. Patented Aug. 28, 1917.

Application filed June 24, 1916. Serial No. 105,527.

To all whom it may concern:

Be it known that I, WILLIAM REIFFERSCHEID, a citizen of the United States, and resident of Chicago, in the county of Cook and State of Illinois, have invented certain new and useful Improvements in Zigzag Radiators, of which the following is a specification.

This invention relates to certain new and useful improvements in that class of radiators or apparatus used for cooling the water which is employed over and over again for keeping the cylinders of motors at a suitably low temperature, and while it is more particularly intended for use on automobiles in conjunction with the engine-cylinders thereof, yet it is applicable for use in connection with other kinds of motors, and for this reason, I wish it understood, that I do not limit myself in its use or application, but may employ it wherever it may be found practicable.

The invention consists in certain peculiarities of the construction, novel arrangement and operation of the various parts thereof as will be hereinafter more fully set forth and specifically claimed.

The principal object of the invention is to provide a liquid cooling radiator, or apparatus of the above mentioned general character, which shall be simple and inexpensive in construction, strong, durable and efficient in operation, with its parts so made and arranged with respect to one another, that a maximum of cooling surfaces in a minimum of space will be afforded, to the end, that the warm or heated water will be more quickly cooled to the proper degree, as it passes through the apparatus, than has heretofore, generally, been accomplished. Another object is not only to greatly increase the lengths of the conduits through which the water passes, but also to so construct them, that they will cause the water to traverse them in thin sheets, and in such a manner that its progress will be somewhat retarded, thus subjecting the water to currents of air forced between the conduits by the movement of the automobile, or if desired, by means of a mechanically driven fan.

Still another object of the invention is to provide means for securely bracing or holding the water-tubes or conduits so that they will not become displaced by vibrations or rough usage, and so that they will not contact with each other, or other parts, which might communicate heat thereto. A further

object is to so construct the conduit as to allow for expansion in the case of the water freezing therein.

Numerous other objects and advantages of the invention will be disclosed in the subjoined description and explanation.

In the accompanying drawing which serves to illustrate an embodiment of the invention—

Figure 1 is a fragmental face view, partly in elevation and partly in section, of a zigzag radiator or water cooling apparatus constructed according to my invention.

Fig. 2 is a side view thereof.

Fig. 3 is an enlarged fragmental view of two of the water conveying conduits illustrating by dotted lines, portions of the brace bars or connecting members used for securing the conduits together, and

Fig. 4 is an enlarged cross-sectional view of one of the conduits showing the manner of constructing the same.

Like numerals of reference refer to corresponding parts throughout the different views of the drawing.

The reference numeral 5 designates the frame or body of the radiator, which may be made of any size, form and material, but by preference, rectangular in shape and of metal. The frame or body 5 is provided at its upper end with a water receiving chamber or compartment 6 to which water may be supplied through a suitable tube 7, located on the top of the casing of the chamber 6 and communicating therewith. The chamber casing 6 also has in its upper portion a nipple 8 to which a tube or pipe leading from a suitable source of water supply 9 may be connected. The lower end of the frame or body 5 is provided with another chamber or casing 9 for water, which has leading therefrom, a nipple 10 to which a pipe or tube, for the circulation of water may be connected at one of its ends. As is clearly shown in Fig. 1 of the drawing, the bottom 11 of the chamber casing 6 is provided with a series of transversely disposed slots 12, and that the top 13 of the chamber casing, at the bottom of the frame or body of the radiator, is provided with a series of transversely disposed slots 14, which are located directly under the slots 12, and in register therewith. Located at their upper and lower ends in the slots 12 and 14 respectively, and secured there by solder or otherwise, are the water conveying conduits, each of which is designated as a whole by the reference numeral

15, and are located vertically within the frame 5, and in parallelism with each other as is clearly shown in Fig. 1 of the drawing. Each of the conduits 15 consists of two elongated pieces of sheet metal 16 and 17, see Fig. 4, which pieces are provided at their edges with overlapping flanges 18 and 19 respectively, which flanges can be soldered together or otherwise united so as to prevent leakage. Near each of its edges, each of the members 16 and 17 of each of the conduits, is formed with an outwardly extended angular portion 20 which portions will produce an enlargement 21 in the cavity of the conduit, near each of its edges, which construction not only reinforces or strengthens the conduit, but also provides for expansion in the event of water freezing in the conduit.

As is clearly shown in Figs. 1 and 3 of the drawing, the conduits are formed of zig-zag shape and are so located with respect to one another that the apices 22 of one of the conduits will be in a vertical line with the apices of the conduit adjacent thereto, yet at a distance therefrom. By this arrangement I am enabled to secure the conduits together at each of the edges thereof, by simply placing a bar or connecting member 23 on the said apices and soldering said bar thereto, which bar may also be secured by solder or otherwise to the lower portion of the chamber casing 6 and the upper portion of the chamber casing 9 as will be readily understood by reference to Fig. 1 of the drawing.

As the flanges 19 on the member 17 of each of the conduits overlap the flanges 18 on the other member 16 of said conduit, it is apparent that by terminating the flanges 19 near the apices of the conduits, in alignment, as at 24 in Fig. 3 of the drawing, shoulders will be provided against which the bars 23 may rest at one of their edges, which construction adds rigidity and strength to the parts.

Located on the inner surface of one side of the chamber casing 6, at the top of the frame of the radiator, is an overflow pipe 25, which extends through the bottom 11 of said casing and is adapted to be inserted into the upper end of the pipe section 26, which is located vertically within the frame 5 and is extended through the chamber casing 9 as is clearly shown in Fig. 1 of the drawing. By this arrangement it is evident that the drain pipes are concealed from view and are protected from injury. By reference to Figs. 1 and 3 of the drawing, it will be observed that the zig-zag conduits are formed with very acute angles, so that they may be placed closely together without touching each other, to the end that, cooling air may be passed between them to contact

with a greatly increased exterior surface of each conduit, than if said conduits were made straight, or of less acute angles, which I prefer to be about $22\frac{1}{2}$ degrees each from a base line 27, see Fig. 3 of the drawing, and so that the progress of the water through the conduits will be retarded, so as to give the air a better chance to cool the same.

Having thus fully described my invention, what I claim as new and desire to secure by Letters-Patent is—

1. In an apparatus of the character described, the combination with a frame or body having water chambers at its top and bottom, of means for inlet of water to the upper chamber and for the outlet of water from the lower chamber, a plurality of conduits vertically located within the frame in spaced relation to one another between said chambers and having communication therewith, the said conduits being of zig-zag form with acute angles and arranged with their adjacent apices overlapping a vertical line, and a connecting member secured to said apices and to the frame.

2. In an apparatus of the character described, the combination with a frame or body having water chambers at its top and bottom, of means for inlet of water to the upper chamber and for the outlet of water from the lower chamber, a plurality of conduits vertically located within the frame in spaced relation to one another between said chambers and having communication therewith, the said conduits being of zig-zag form with acute angles and arranged with their adjacent apices overlapping a vertical line, and a connecting member secured to said apices at each of the edges of the conduits.

3. In an apparatus of the character described, the combination with a frame or body having water chambers at its top and bottom, of means for inlet of water to the upper chamber and for the outlet of water from the lower chamber, a plurality of conduits vertically located within the frame in spaced relation to one another between said chambers and having communication therewith, the said conduits being of zig-zag form with their inclined parts located at substantially twenty two and one-half degrees from a horizontal line drawn through their apices and said conduits arranged with their adjacent apices overlapping a vertical line, and a connecting member secured to said apices and to the frame.

WILLIAM REIFERSCHEID.
